TOOTH PASTE OR SHAVING CREAM
DISPENSER

Arthur R. Kach, Ashtabula, Ohio

Application July 22, 1938, Serial No. 220,725

13 Claims. (Cl. 221—60)

This invention relates, as indicated, to tooth paste or shaving cream dispensers, but has reference more particularly to devices of this character having associated therewith means for supporting various toilet articles.

The primary object of the invention is to provide devices of the aforesaid character which are compact in form and which consist of a minimum number of readily assembled inexpensive parts.

To the accomplishment of the foregoing and related ends, said invention, then, consists of the means hereinafter fully described and particularly pointed out in the claims.

The annexed drawings and the following description set forth in detail certain structures embodying the invention, such disclosed means constituting, however, but several of various structural forms in which the principle of the invention may be used.

In said annexed drawings:

Fig. 1 is a plan view of a preferred form of the device; Fig. 2 is a right side elevation of the device shown in Fig. 1; Fig. 3 is a horizontal cross-sectional view taken on the line 3—3 of Fig. 4; Fig. 4 is a vertical cross-sectional view taken on the line 4—4 of Fig. 1; Fig. 5 is a vertical cross-sectional view taken on the line 5—5 of Fig. 1; Fig. 6 is a perspective view of one of the bracket members; Fig. 7 is a plan view of a modified form of the device; Fig. 8 is a front elevation of the device shown in Fig. 7; Fig. 9 is a right side elevation of the device shown in Figs. 7 and 8; Fig. 10 is a vertical cross-sectional view taken on the line 10—10 of Fig. 7; Fig. 11 is a plan view of another modified form of the device; Fig. 12 is a right side elevation of the device shown in Fig. 11; Fig. 13 is a vertical cross-sectional view taken on the line 13—13 of Fig. 11; Fig. 14 is a horizontal cross-sectional view taken on the line 14—14 of Fig. 13; and Fig. 15 is a vertical cross-sectional view of a somewhat modified form of the device shown in Fig. 11.

Referring more particularly to that form of the invention shown in Figs. 1 to 6 inclusive, the device comprises a pair of complementary bracket members 1 and 2, respectively provided with in-turned flanges 3 and 4, such flanges being in abutment with each other and preferably seam welded along their meeting edges. The flanges 3 and 4 are provided with apertures 5 through which screws 6 may be inserted for the purpose of securing the bracket to the wall of a bathroom or the like. Disposed between the bracket members 1 and 2 is a pair of soft rubber rollers

7 and 8, which are respectively molded about shafts 9 and 10, the ends of which project somewhat beyond the bracket members and are journaled in the latter. The shaft 10 extends a considerable distance beyond the bracket member 2 and the end of the extension is slotted for the reception of a handle 11 which is pinned to the shaft. The handle 11 is preferably in the form of a sheet metal stamping, and by means of such handle, the roller 8 may be rotated. It may be noted at this point that the axes of the shafts 10 and 11 are parallel and that such axes are spaced from each other a distance considerably less than the diameter of either roller 7 or 8. Stated in another manner, the axes of the shafts 10 and 11 are spaced apart a distance less than the sum of the radii of the rollers 7 and 8. The purpose of thus spacing the rollers will presently be described.

Mounted upon the bracket members 1 and 2 is a shelf-like member 12 formed of a molded plastic material and having a downwardly extending flange 13 at the front and sides thereof, such flange forming a skirt which effectively conceals from view the rollers 7 and 8 and parts of the bracket.

Formed integrally with the member 12 and projecting downwardly from the lower surface thereof is a projection 14 which extends into the space between bracket members 1 and 2 above and to the rear of the roller 8 and is apertured at its ends for the reception of screws 15 whereby the member 12 is secured to the bracket, such screws extending through apertures 16 in the bracket members. The projection 14 has a lower curved surface 17 which is substantially concentric with the roller 8 and is spaced somewhat from the peripheral surface of the latter. The member 12 has a series of spaced oval-shaped openings 18 therein of a size sufficient to receive the handle portions of tooth brushes T. Disposed immediately in front of these openings is an upstanding ledge 19, which is formed integrally with the member 12 and is adapted to support the brush portions of the brushes T in somewhat spaced relation from the shelf 12, as shown in Figs. 2 and 4. This permits air to gain access to the space under such brush portions, such air passing upwardly through the brush portions and drying the bristles thereof. Such member 12 has also formed in its upper surface a cavity or recess 20 of a size sufficient to receive a glass tumbler.

The skirt 13 of the member 12 is cut away as

at 21 in order to enable the skirt to accommodate the shaft 10 when the parts of the device are assembled.

The bracket is preferably formed of sheet metal so as to afford sufficient supporting strength for the device, while the holder 12 is formed of a plastic molded material, such material being chosen for its sanitary properties as well as for its lightness and the ease with which it may be formed into any desired shape.

The rollers 7 and 8 are assembled on the bracket at the time the bracket members are secured together and the edges of the flanges 3 and 4 welded to each other.

15 In the use of the aforesaid device, the tube of tooth paste S is held in inverted position, as shown in Figs. 2 and 4, and the flattened base or upper end of the tube is inserted between the rollers 7 and 8. The handle 11 is then rotated, 20 and, due to the conjoint squeezing action of the rollers 7 and 8, resulting from such rotation, the tube is squeezed and the contents thereof expelled in desired amounts, depending upon the extent to which the handle is turned.

25 Due to the use of soft rubber rollers and the spacing of these rollers which has been described above, the tube is squeezed in a desired manner without the use of springs and gears and other interconnecting driving members between the 30 rollers such as characterize most devices of this character. The spacing of the rollers is such that in moving the tube upwardly and squeezing the same, they are distorted in the manner indicated in Fig. 4.

35 In moving the base of the tube upwardly, as shown in Fig. 4, the latter comes into contact with the curved surface 17 of the projection 14 and is deflected by such surface rearwardly and then downwardly substantially parallel with the 40 axes of the tube. In this way, the evacuated portions of the tube are concealed from view, and the articles on the shelf 12 are in no way disturbed.

It will be apparent from the foregoing that a 45 device has been provided which is readily assembled and consists of a minimum number of easily manufactured and inexpensive parts.

Referring now to that form of the invention shown in Figs. 7 to 10 inclusive, this device is 50 more particularly adapted for use by shavers, but the construction of the device is somewhat similar to that of the previously described form of the invention. It consists of bracket members 1' and 2' which are somewhat longer than the bracket members 1 and 2. In this case, due to the length of the bracket members, a separate projection 25 is formed on the lower surface of the shelf-like member 12' into the ends of which 55 screws 15' which secure the member 12' to the bracket members are inserted. In addition, screws are also inserted through the bracket members into the ends of the projection 14', which corresponds to the projection 14 in the 60 previously described form of the invention. The member 12' has formed in its upper surface a recess 26 for shaving lotion or the like, a recess 27 for talcum powder or the like, a recess 28 for a razor, a recess 29 for razor blades, a recess 30 65 for a shaving brush, and a recess 31 for a styptic pencil. The holder in this case thus serves to hold all of the articles ordinarily used for shaving.

In that form of the device shown in Figs. 11 to 14 inclusive, the holder 12'' is provided with a flanged skirt 13'' at only the front and left side

thereof, the other side being unflanged and closed by means of the bracket member 2'', as shown more clearly in Fig. 14.

In that form of the device shown in Fig. 15, the device is constructed similarly to that shown in Figs. 11 to 14 inclusive, but in this case the deflector is omitted and instead a slot 32 is formed in the portion of the shelf member 12''' directly above the meeting faces of the rollers, and through which the evacuated portion of the 10 tubes passes. The member 12''' in this case has formed on its lower surface a projection 33 to the ends of which the screws which secure the member 12''' to the bracket are secured.

Other modes of applying the principle of my 15 invention may be employed instead of the one explained, change being made as regards the structure herein disclosed, provided the means stated by any of the following claims or the equivalent of such stated means be employed.

I therefore particularly point out and distinctly claim as my invention:

1. In a dispenser for tooth paste and the like, a metallic bracket adapted to be secured to a wall, and a holder for toilet articles mounted on 25 said bracket, said holder having tube deflecting means formed integrally therewith.

2. In a dispenser for tooth paste and the like, a bracket adapted to be secured to a wall, and a holder for toilet articles mounted on said bracket, 30 said holder having a projection formed integrally therewith, said projection having a curved surface adapted to deflect downwardly the evacuated portion of a tube of tooth paste.

3. In a dispenser for tooth paste and the like, 35 the combination of a supporting bracket having a pair of parallel coacting tube squeezing rolls, means for rotating said rolls whereby to force upwardly a tube the base of which has been inserted in said rolls, and means disposed adjacent 40 said rolls and independent of said supporting bracket for deflecting downwardly the portion of the tube which has passed through said rolls.

4. In a dispenser for tooth paste and the like, 45 the combination of a supporting bracket having a pair of coacting tube squeezing rolls mounted therein, a holder for toilet articles mounted on said bracket and provided with means for deflecting in an opposite direction the portion of a tube which passes through said rolls.

5. In a dispenser for tooth paste and the like, 50 a holder having a substantially horizontal upper surface of substantial area for supporting toilet articles, and a projection on the lower surface thereof, said projection having an arcuately 55 curved surface.

6. In a device of the character described, a 60 holder for toilet articles, comprising a shelf-like member having openings therein for the reception of the handles of tooth brushes, and means adjacent said openings for supporting above the level of said member the brush portions of said tooth brushes.

7. In a device of the character described, a 65 holder for toilet articles, comprising a shelf-like member having openings therein for the reception of the handles of tooth brushes, and a ledge formed integrally with said holder and extending alongside said openings, said ledge adapted to 70 support the brush portions of said brushes in spaced relation to the upper surface of said member.

8. In a device of the character described, a 75 bracket adapted to be secured to a wall of a room,

5 a holder for toilet articles mounted on said bracket, said holder having means associated therewith for deflecting the evacuated portion of a tube of tooth paste, and means extending through the walls of said bracket and into said deflecting means for connecting the holder to the bracket.

9. In a device of the character described, a bracket adapted to be secured to the wall of a room, and a holder for toilet articles mounted on 10 said bracket, said holder having a projection formed integrally therewith and having a curved deflecting surface, and means extending through said bracket and into the ends of said projection for connecting the holder to the bracket.

15 10. In a device of the character described, a bracket adapted to be secured to the wall of a room, a holder for toilet articles having a projection formed integrally therewith, and means 20 extending through said bracket and into the ends of said projection for securing said holder to said bracket.

11. In a device of the character described, a bracket formed of sheet metal and adapted to be 25 secured to the wall of a room, a holder for toilet articles formed of molded plastic material and

having an integral projection on the lower surface thereof, and screws extending through said bracket and into the ends of said projection for securing the parts of the device to each other in properly assembled relation.

12. In a device of the character described, a bracket formed of sheet metal and adapted to be secured to the wall of a room, a holder for toilet articles mounted on said bracket, said holder formed of molded plastic material and 10 having downwardly extending flange portions at the front and one side thereof, said flange portions and one side of said bracket constituting a skirt for said device, and means securing said holder to said bracket.

15 13. In a device of the character described, a bracket adapted to be secured to the wall of a room, a holder for toilet articles mounted on said bracket, and a pair of coating tube squeezing rolls journaled in said bracket, said holder having 20 an opening therein disposed directly above the contacting portions of said rollers for receiving the evacuated portion of a tube of tooth paste or shaving cream.

ARTHUR R. KACH. 25
